7 Claims. (Cl. 89—176)

1

This invention relates to breech-loading guns or missile-projectors of the kind usually known as semi-automatic in that after being fired they are automatically recocked.

In such weapons it is advantageous to mount both the breech block and barrel to slide relatively to a fixed casing and to one another upon release from cocked positions in which they are independently held, so that they are both dynamic, that is to say, move rapidly forwards in order to fire the weapon and to make the firing take place before the end of the run-out stroke. As a result, the kinetic energy of all the forwardly moving parts is used to absorb part of the recoil forces and a further part is absorbed during the return stroke in storing up energy in a recuperative device, which is usually a spring but may be, for example, a compressed gas, by which the breech block is driven forward again on the next firing stroke. In weapons so constructed there are usually separate recuperative devices for both the breech block and barrel, and the extent of the travel of the parts is limited by the disposition of these devices.

I aim at obtaining substantial absorption of the recoil forces by the kinetic energy of the forwardly moving parts with a relatively low maximum recoil thrust. For this purpose the moving parts must have a long recoil, and the usual objection to this is that the overall length of the weapon is increased. By my invention I attain my object without having to make the overall length large.

In weapons constructed as described, the breech block and barrel must be locked together at the moment of firing in order that the breech block, which, of course, directly takes the recoil force when the weapon is fired, may initiate the rearward movement of the barrel. Hitherto the locking mechanisms used have necessitated lengthening the breech block to accommodate them and so have led to the overall length of the weapon being longer than it otherwise need be. In a weapon of given characteristics any reduction in the overall length is highly desirable. In addition the impact forces involved are considerable, and it is not simple to provide a mechanism which will engage without difficulty during the run-out stroke and yet will withstand the stresses well.

My invention will be most clearly understood by the following description of the preferred form of gun, which will now be described by way of example with reference to the accompanying drawings, in which:

Figure 1 is a side elevation of the gun and of a missile about to be loaded into it;

Figure 2 is a longitudinal section with the parts in the cocked position;

Figure 2a is a continuation of Figure 2;

2

Figure 3 is a view similar to Figure 2 with the parts in the fully run-out position;

Figure 3a is a continuation of Figure 3;

Figures 4 and 5 are sections on the lines IV—V and V—V in Figures 2 and 3 respectively;

Figures 4a and 5a are continuations of Figures 4 and 5 respectively;

Figure 6 is a section on the lines VI—VI of Figure 3, the breech block having been omitted for clarity.

Figure 7 is a section along the line VII—VII of Figure 3.

Figure 8 shows the breech block on a larger scale;

Figure 9 is a section on the line IX—IX in Figure 2;

Figure 10 is a section on the line X—X in Figure 9.

Figures 11 and 12 are a plan and an elevation respectively of the breech tube;

Figure 13 is a plan of the mechanism which locks the breech tube to the barrel; and

Figure 14 is a detailed elevation of the mechanism for checking the forward movement of the breech tube and engaging the locking mechanism.

The parts of the gun that may be regarded as stationary during the firing operation include a breech casing 1 furnished with a butt or shoulder piece 2 and slotted as shown 3 so that a missile 4 in the form of a bomb can be loaded at the breech. A pistol grip 5 is fixed to the casing 1 and a trigger 6 is connected to a rod 7 which can bear on a member 8 that is rigid with a rearward cocking sear 9 which is engaged by a spring 10 carried in the butt 2. Both the trigger rod 7 and the sear 9 pass through a back plate 11.

A breech block 12 with which a forwardly projecting tube 13 is rigid is held by the rearward sear 9 in the cocked position, the sear latching under a bent 14, and the breech block slides within the casing 1 during the firing operation.

The barrel 15 of the gun extends within the breech tube 13 and also slides in the casing 1 during the firing operation, that is to say, the breech block and barrel are both slideable relatively to the breech casing. At its rearward end the barrel is formed with a skirt 22 and at its forward end it is surrounded by a spring 16, the

inner end of which bears on interrupted stops 17 formed at the outer end of the casing 1 and the outer end of which bears on the inside of a dust cover 18 fixed to the end of the barrel. Part of the spring 16, which serves to run out the

barrel, lies within the breech block tube 13 and the dust cover 18 extends rearwardly sufficiently to protect the remainder of the spring 16 at all times. The tube 13 is slotted twice as shown at 19 over the greater part of its length so that it

60 consists essentially of two part-cylindrical arms

united together at each end. These slots 19 serve several purposes; they allow the tube to pass the stops 17, they provide spaces through which lugs 26 can project outwards from the barrel skirt 22 and they allow the missile to be inserted in the breech chamber.

The barrel 15 is held against the action of the spring 16 in the cocked position by two forward sears 20, one on each side of the gun, which engage the forward shoulder of the skirt 22. Each sear 20 is recessed at its rearward end to receive the enlarged head of a lever 50, pivoted at 51 and formed with a cam surface 52 which is struck by a projection 53 on the breech block tube 13 and then moves outward, carrying the sear 20 with it. Thus the breech block in its forward movement releases the barrel, which thereupon moves forward under the action both of the spring 16 and of the breech block itself.

The breech block is run out by springs 23, which are of such strength that they move the block faster than the barrel is moved by the spring 16. These springs 23 bear at one end on the back plate 11 and at the other end on lateral brackets 24 rigid with the breech block tube 13, and they are housed in lateral compartments 25 of the casing 1.

When the weapon is to be fired, movement of the trigger 6 trips the cocking sear 9, so that the breech block is run out by the springs 23. In the travel of the breech block the projections 53 strike the cam surfaces 52 of the sears 20 and trip them, so that the barrel is also run out by the spring 16. As the springs 23 are relatively stronger than the springs 16, and the breech block has considerable forward velocity before the barrel begins to move, the barrel is almost immediately struck by the breech block, which thus helps to drive it forward.

In the course of the forward stroke the block and barrel may advantageously be automatically locked together, e. g. by means of one or more wedge or like members which are positively moved inwards into a locking position, in order that the block (which, of course, directly takes the recoil force when the weapon is fired) may initiate the rearward movement of the barrel. This lock is released during the return stroke at a point at which the barrel already has enough kinetic energy to continue its movement into the recocking position.

In the gun illustrated, this locking is effected by two wedge members 75, diametrically opposed to one another. Each wedge member engages between two forward lugs on the breech-block tube 13 and a single rearward lug 26 on the barrel skirt 22. The lugs on the breech-block tube are formed by making transverse slots 28 in the edges of the arms of the breech-block tube, the forward edges of these slots forming shoulders which act as the breech-block lugs. During the forward movement of the breech block and barrel it is immaterial whether there is a positive lock longitudinally between the two, so some end play may be allowed between the wedge members 75 and the lugs formed by the walls of the slots 28. This is advantageous because it allows the wedge members to enter the gap between the lugs without difficulty as the parts move forward. Each wedge member 75 is carried by an arm 29 which is fixed to a cross-pin 30 which can rock in a bearing 31 on a reinforcement 32 on the barrel. Each wedge member is positively moved inwards into the locking position during the run-out of the weapon by engagement with

a part carried by the casing 1. This action is effected by the nose 60 of a lever 61 which is pivoted by means of a pivotally mounted supporting sleeve at 62 through which the rod 69 slidably extends and is rocked inwards about its pivot by a striker 63 which is pivoted at 64 and subjected to the action of a spring 65. This striker is engaged by the reinforcement 32 of the barrel as the latter is run out and knocks the nose 60 of the lever 61 inwards so that it is moved into the path of the roller 33 on the end of wedge member 75 whereby the forward movement of the roller, which is moving with the barrel assembly, causes it to be forced inwards so that in turn the arm 29 is moved inwardly about its pivot.

It may happen that the barrel tends to move forwards too fast relatively to the breech block. In order to slow up the barrel in such a case retarding springs 69 are provided and are arranged surrounding the levers 61 and interposed between their heads and their pivot sleeves 62 so that the levers will move with the barrel against the action of the springs and retard the barrel. Since the rods are slidable in the pivotally supported sleeves 62, they may slide as well as rock when the barrel reinforcement strikes the noses 60 of the rods. If the barrel is moving forward too fast relatively to the breech block assembly, when the end of the lever 61 is moved inwards to engage the roller 33, the lever 61 will be caused to slide forward through the collar 62 against the action of the spring 69, thus retarding the forward movement of the roller to allow the breech block to catch up with the barrel assembly, when the wedges 75 will be forced inwards into the slots 28.

The weapon is now fired. The precise means by which the firing is effected are not material to the present invention, but in the gun shown in

the drawings the positive inward movement of the upper wedge arm 29 is used to actuate the firing mechanism. This wedge arm has an inwardly projecting nose 54 which trips a firing sear 37 carried in a sear holder 38 and so allows a firing pin 35 to be driven forwards by a spring 36. The firing pin is rigid with the cocking bent 14 and in the cocked position the nose of the sear 37 engages it through a slot 39 in the body 40 of the breech block. Since the rods 61 are slidable in the pivotally supported sleeves 62, they may slide as well as rock when the barrel reinforcement strikes the noses 60 of the rods. If the barrel is moving too fast, the rods will not only be rocked but will slide through the pivoted sleeves against the action of the springs 69, which will produce a braking effect.

The explosive force produced when the weapon is fired acts on the face of the breech block, with the immediate result that any lost motion between the wedge members 75 and the walls of the slots 28 is taken up, and the block and barrel move backwards together. During the initial small movement of the breech block backwards relatively to the barrel, the cartridge case may move backwards from the barrel under the force of the explosive gases. Support must therefore be given to the cartridge case, and this is afforded by the inner wall of the barrel skirt 22. The forward end of the breech block 12 constitutes a spigot-like part which projects telescopically into the skirt 22, as clearly shown in Figure 8, so as to form a chamber within which the cartridge case can move with its wall supported by the wall of the skirt. The lost motion provided by the play between the wedge members and lugs is again ad-

vantageous, as it allows some absorption of the recoil forces to take place before the breech block begins to move the barrel backwards and so reduces the immediate impact stresses. It is also advantageous that when the lost motion is taken up the lugs 26 make direct contact with the wedge members 75, which in turn make direct contact with the lugs formed by the edges of the slots 28, so that the stresses are directly transmitted to these parts. When the parts have travelled backwards over some distance the wedge members are moved out of the locking position by the engagement of rollers 33 mounted on the ends of the wedge members 75 with obliquely slanting forward ends of ramps 66 rigid with the casing 4. The wedge members are thus positively lifted out of the locking position and thereafter the block is free to move rearwards independently of the barrel and will in fact move out of contact with the barrel. Its movement continues until it is caught and held by the cocking sear 9. To damp its final rearward movement a buffer spring 42 is fixed in the tail of the block to come into contact with the face of the plate 11. The barrel is caught by the forward sear 20. To ensure that this recocking cannot be prevented by pressure on the trigger a projection 41 is provided on the rod 7 in the path of a projection 67 on the breech block so that the rod 7, which is located within a bulged part of the casing 4, is rocked radially outwards against a spring as the breech block is returned to cocked position, and so enables the cocking sear 9 to return to the position in which it can catch the breech block. In the cocked position this projection 41 is clear of the projection 67. When the breech block runs back to its limit, the hooked nose of the cocking sear 9 engages with the bent 14. The breech block, which is the casing for the firing pin and its spring, is then urged forward by the very powerful breech block springs 23, which overcome the small firing spring 36, compress it, and thus retract the firing pin.

Both the block and barrel are thus recocked, that is to say, the weapon automatically opens its own breech for loading, and the cycle is complete.

The extent to which the kinetic energy of the barrel is effectively utilised in absorbing part of the recoil forces depends, of course, upon the relative weights and disposition of the parts. Even if the kinetic energy of the barrel is not effectively utilised, the invention, as exemplified by the gun illustrated, includes the combination in a weapon of a body, a breech block movable relatively to a breech casing and a barrel movable relatively to both the breech block and the breech casing, the breech block being positively locked to the barrel at the moment of firing and both the locking and unlocking being automatically effected by movement of the barrel relatively to the body.

I claim:

1. In a semi-automatic weapon comprising a fixed casing and an assembly slidable in the casing between a rearward cocked position and a forward firing position, said assembly comprising a barrel and a breech block movable relative thereto, a forward extension rigid with said breech block and extending telescopically over said barrel, forward lug-forming means on said extension, rearward lug-forming means carried

by said barrel, latch means mounted outside and movable with said assembly to move radially inwards between said forward and rearward lug-forming means, and means for causing radial movement of said latch means into latching position during forward movement of said assembly.

5 2. A semi-automatic weapon as defined in claim 1, in which said forward lug-forming means is constituted by the forward wall of a lateral slot made in said extension.

10 3. A semi-automatic weapon as defined in claim 1 in which said extension is slotted to receive said rearward lug-forming means.

15 4. A semi-automatic weapon as defined in claim 1 in which said latch means is mounted on the barrel.

20 5. A semi-automatic weapon as defined in claim 1 in which said movement causing means are carried by the casing to act on latch means in cam fashion.

25 6. A semi-automatic weapon as defined in claim 1 in which rollers which are carried on said latch means are engaged by ramps rigid with the casing during rearward movement of said barrel assembly, to effect unlocking of said breech block and said barrel assembly.

30 7. In a semi-automatic weapon comprising a fixed casing and an assembly slidable in the casing between a rearward cocked position, and a forward firing position, said assembly comprising a barrel and a breech block movable relative thereto, and said assembly being adapted to absorb a substantial part of the recoil energy developed upon firing, a forward extension rigid with said breech block and extending telescopically over said barrel, forward lug-forming means on said extension, rearward lug-forming means carried by said barrel, and latching means carried by said barrel to engage between said forward lug-forming means and said rearward lug-forming means, said latching means being of

35 such size as to provide lost motion between the breech-block and barrel, when entered between said forward and rearward lug forming means.
